EDDO V. BATES, OF LOWELL, MASSACHUSETTS, ASSIGNOR OF ONE-HALF TO ROBERT B. ROBINSON, OF DRACUT, MASSACHUSETTS.

BREAST FOR CARDING-MACHINES.

1,103,649.

Specification of Letters Patent. Patented July 14, 1914.

Application filed September 24, 1913. Serial No. 791,643.

To all whom it may concern:

Be it known that I, EDDO V. BATES, a citizen of the United States, residing at Lowell, in the county of Middlesex and State of Massachusetts, have invented certain new and useful Improvements in Breasts for Carding-Machines, of which the following is a specification.

This invention relates to carding machines especially to those used in the handling of wool fibers.

It is substantially an attachment for carding machines which takes the stock before it is well started on the main cylinder and breaks up the lumps, mixes and strengthens the stock and saves wear and tear on the card clothing in various ways and especially by preventing lumps on the main cylinder which lumps have a tendency to wear out the card clothing in spots. If such lumps get on to the main cylinder, they are forced well into the teeth thereof and although the workers pick off small quantities, the lumps are not entirely destroyed but are finally removed with the web by the fancy and doffer and make uneven work. My device breaks up and destroys these lumps before they reach the main cylinder and delivers to it a thin, even, unbroken web. My device also thoroughly mixes the stock and helps to straighten the fibers before they reach the main cylinder. It permits the speed to be increased thus increasing the production and helps to produce a better and stronger yarn with less waste. This attachment may be placed upon any card either the first breaker, second breaker, intermediate or finisher.

My device can be placed upon a card of any usual construction with very slight changes therein and without occupying any additional floor space.

In the drawings, Figure 1 is a side elevation of a carding machine with my attachment.

H is the main cylinder, 10, 10 are the workers, 11, 11 are the strippers therefor, 12 is the fancy and 13 is the doffer all of the usual construction. The feeding-in rolls K and L and the licker-in E are also of the usual construction except that the teeth of the licker-in are reversed and it travels in the opposite direction to what is customary thereby taking the stock S and carrying it downward underneath and then up instead of over and down as is customary.

The tumbler F is unchanged and the first worker C is similar to the workers 10 as its teeth pitch in the same direction and it rotates in the same direction with the other workers.

40 is the main frame of the card and 41 is a rearwardly extending bracket of a well known construction which supports the licker-in, the feeding-in rolls, the tumbler and my attachment.

Instead of being in contact with each other, I separate the licker-in E from the tumbler F and over them in engagement with both, I locate what I will call a breast cylinder D. This breast cylinder is preferably somewhat larger than the workers but considerably smaller than the main cylinder. It rotates in the same direction with the main cylinder and its teeth pitch in the same direction with those on the main cylinder. This breast cylinder D is in carding proximity to worker C and I use in connection therewith, an additional worker A, the teeth of which pitch in the same direction with worker C but which rotates in the opposite direction. Worker A and breast cylinder D are in carding proximity. I also use a stripper or transfer roll B whose teeth pitch in a direction opposite to those of workers A and C and which rotates in the same direction with worker C. Stripper or transfer roll B is in engagement with worker A, breast D, and worker C.

In regard to speed, workers A and C have about the same surface speed which is 90 slower than that of breast D or main cylinder H. Stripper or transfer roll B has a surface speed faster than workers A or C but slower than breast D.

Breast D has a surface speed faster than 95 licker-in E or workers A or C or stripper B. Tumbler F has a surface speed faster than breast D but slower than main cylinder H.

Considering the tops thereof, main cylinder H, breast D, and worker A travel from 100 left to right while licker-in E, tumbler F, worker C, and stripper B travel from right to left. Considering the tops thereof, the teeth of main cylinder B, breast D and workers A and C pitch to the right, while 105 those on licker-in E, tumbler F and stripper B pitch to the left. Adjoining cylinders and rolls are all so set that their teeth are in carding or stripping proximity to each other. The result of this construction is that the 110

stock S is delivered by feeding-in rolls K and L to licker-in E by which it is carried around and delivered to breast D by which it is carried along. It is carded between 5 worker A and breast D and part of it 20 is carried around by worker A and stripped therefrom by stripper B being carried along thereby and returned to breast D by which the stock is still carried along and is carded 10 again by worker C, some 21 being carried along thereby and carded by main cylinder H and some 22 being still carried by worker C and stripped therefrom by stripper B and with the stock 20 returned by it again to 15 breast D where the process is repeated. Another part of the stock 23 after being carded by worker A is again carded by the worker C and the main cylinder H and part 24 is carried along by breast D and is stripped 20 therefrom by tumbler F and deposited on the main cylinder H as shown.

It will be seen that there are carding points between A and D, C and D, and C and H and as the arrangement is a reworking one, the stock is repeatedly worked between A, B, C and D until it is in such shape as to be finally carried along by the main cylinder H to the other workers 10. It is carded by these, stripped therefrom by 30 strippers 11 and finally taken from main cylinder H by the action of fancy 12 and doffer 13 as is customary or by any other means.

It is unnecessary to explain to one skilled 35 in the art that all the rolls and cylinders described are covered with suitable card clothing.

I claim:

1. In a carding machine, a main cylinder, 40 a first worker, a tumbler, a licker-in adjoining but separated from the tumbler, and feeding - in rolls in engagement with the licker-in, combined with a breast cylinder which engages the first worker, the licker-in 45 and the tumbler, an additional worker in carding proximity with the breast cylinder, and a stripper in operative relation with the first worker, the breast and the additional worker.
2. In a carding machine, a main cylinder, 50 a first worker, a tumbler, a licker-in adjoining but separated from the tumbler, and feeding - in rolls in engagement with the licker-in, combined with a breast cylinder 55 which engages the first worker, the licker-in and the tumbler, an additional worker in carding proximity with the breast cylinder, and a stripper in operative relation with the first worker, the breast and the additional 60 worker, all so arranged that the teeth of

the main cylinder, of the breast, and of both workers pitch in the same direction while the teeth of the licker-in, of the tumbler and of the stripper pitch in the opposite direction.

3. In a carding machine, a main cylinder, a first worker, a tumbler, a licker-in adjoining but separated from the tumbler, and feeding - in rolls in engagement with the licker-in, combined with a breast cylinder 70 which engages the first worker the licker-in and the tumbler, an additional worker in carding proximity with the breast cylinder, and a stripper in operative relation with the first worker, the breast and the additional 75 worker, all so arranged that the teeth of the main cylinder, of the breast, and of both workers pitch in the same direction while the teeth of the licker-in, of the tumbler and of the stripper pitch in the opposite direction, and so arranged that the main cylinder, 80 the breast, and the additional worker rotate in one direction while the licker-in, the tumbler, the first worker and the stripper rotate in the opposite direction.

4. In a carding machine, a main cylinder, a first worker, a tumbler, a licker-in adjoining but separated from the tumbler, and feeding - in rolls in engagement with the licker-in, combined with a breast cylinder 90 which engages the first worker the licker-in and the tumbler, an additional worker in carding proximity with the breast cylinder, and a stripper in operative relation with the first worker, the breast and the additional 95 worker all so arranged that the teeth of the main cylinder, of the breast, and of both workers pitch in the same direction while the teeth of the licker-in, of the tumbler and of the stripper pitch in the opposite direction, and so arranged that the main cylinder, 100 the breast, and the additional worker rotate in one direction while the licker-in, the tumbler, the first worker and the stripper rotate in the opposite direction and so arranged 105 that the surface speed of the breast cylinder is faster than that of the licker-in, of the first worker, of the additional worker and of the stripper, while the surface speed of the stripper is greater than that of the first 110 worker and of the additional worker, the surface speed of the tumbler is greater than that of the breast cylinder and less than that of the main cylinder.

In testimony whereof I hereto affix my 115 signature in presence of two witnesses.

EDDO V. BATES.
